UNITED STATES PATENT OFFICE.

GEORGE C. LYON, OF PROVIDENCE, RHODE ISLAND.

DESIGN FOR A HOLDER FOR SODA-WATER TUMBLERS.

No. 38,233.

Specification for Design.

Patented Sept. 11, 1906.

Application filed July 20, 1906. Serial No. 327,097. Term of patent 3½ years.

To all whom it may concern:

Be it known that I, GEORGE C. LYON, a citizen of the United States, residing at Providence, in the county of Providence and State of Rhode Island, have invented a certain new, original, and ornamental Design for Holders for Soda-Water Tumblers, of which the following is a specification, reference being had therein to the accompanying drawing, forming a part thereof, which is a perspective view of said design.

I claim—

The ornamental design for a holder for soda-water tumblers, as shown.

GEORGE C. LYON.
